(57) **CLAIM**

We claim, the ornamental design for a laser scanner, as shown and described.

DESCRIPTION

FIG. 1 is a perspective view of a laser scanner;
FIG. 2 is a top plan view of the embodiment of FIG. 1;
FIG. 3 is a first side plan view of the embodiment of FIG. 1;
FIG. 4 is a front plan view of the embodiment of FIG. 1;
FIG. 5 is a second side plan view of the embodiment of FIG. 1;

FIG. 6 is a rear plan view of the embodiment of FIG. 1; and,
FIG. 7 is a bottom plan view of the embodiment of FIG. 1.
Color tones in the form of tonal shades of gray are not
claimed.

References to “side”, “top”, and “bottom” in the figure
descriptions are not meant to require certain in-use orientation,
a luminaire according to the claimed design may be used
in any orientation.
